W. F. BLAKE,
CLOTHES WASHING MACHINE,
APPLICATION FILED AUG. 18, 1919.

1,345,312.

Patented June 29, 1920.

INVENTOR

William F Blake

UNITED STATES PATENT OFFICE.

WILLIAM F. BLAKE, OF TOLEDO, OHIO.

CLOTHES-WASHING MACHINE.

1,345,312.

Specification of Letters Patent. Patented June 29, 1920.

Application filed August 18, 1919. Serial No. 318,237.

To all whom it may concern:

Be it known that I, WILLIAM F. BLAKE, a citizen of the United States, residing at Toledo, in the county of Lucas and State 5 of Ohio, have invented a new and useful Clothes-Washing Machine, of which the following is a specification.

My invention relates to improvements in clothes washing machines in which a round 10 tub has a bucket plunger operating inside the tub; and the objects of my invention are, first, to provide a washing machine that cleanses garments quickly and efficiently; second, to construct a machine that will wash 15 thoroughly without twisting or tearing the garments; and third, to provide a washing machine that agitates the water, soap, and clothes thoroughly in combination without complicated mechanism inside the tub or 20 outside.

I attain these objects by the mechanism illustrated in the accompanying drawing, in which—

Figure 1 is a vertical section of the outer 25 tub and inner bucket plunger; Fig. 2, a view of the vertical section of the bucket plunger; and Fig. 3, a detail view of the base of the bucket plunger.

Similar numerals refer to similar parts 30 throughout the several views.

Referring to Fig. 1, the figure 1 indicates the operating lever, 2, the connecting shaft between lever 1 and the cross bar 3 of the bucket plunger 5. 4 shows the side standards and 7 the circular disk which forms 35 the base of the bucket plunger and which is cut out as shown at 16 leaving a wide pressure flange with the bevel 8 to facilitate the upward movement of clothes and water.

40 10 indicates the upright fastened to the outside of the tub 6 by the rivets 11. 13 and 14 are the pivots connecting the lever 1 with the upright 10 and the shaft 2. 12 is the spring which assists in bringing up 45 the lever 1 and the bucket plunger 5. 17 shows the wall of the bucket plunger 5 and 18 the air space between the base 7 and the bottom of the tub 6. In the operation of 50 my washing machine, water and soap are placed in the tub 6 filling it to about the same depth as the top of the bucket plunger 5, then the garments are put into the water and inside of the bucket plunger. The bucket plunger 5 is moved up and down in

the tub 6 by means of the lever 1. When 55 the bucket plunger is lifted it carries part of the water and clothes upward with it then gravity causes the garments and water to plunge toward the bottom of tub 6 through the opening 16; now when the 60 bucket plunger 5 is pressed down, the circular flange 7 on the bucket plunger displaces the water and clothes causing them to rush rapidly upward through opening 16. This action repeated quickly creates an 65 enormous agitation and intermixing of clothes and water, forcing soapy water constantly through the garments and thus cleansing them quickly without tearing or twisting the fabric. 70

The bucket plunger or drum 5 provides a receptacle for the clothes and the aperture in the disk 7 of the plunger being considerably less in area than the area of the tub and the plunger or bucket also quite closely 75 fitting the tub, movement of the plunger causes the water and clothing to be forced upwardly and downwardly through this central aperture, the rapidity of action being caused by the displacement of the 80 plunger. While gravity may have some effect on the water particularly on its downward movement upon the upward movement of the plunger, the principal cause of agitation however is by reason of the displacement of the plunger. It is to be noted that, 85 on downward movement of the plunger, water passing therethrough is forced toward the center with an equal pressure from all sides and upon upward movement of the 90 plunger the water is drawn downward through the plunger moving in the reverse direction with equal pressure on all sides. The clothing in the drum is not caused to become tangled or knotted to any detrimental extent at least because of the fact that the movement of the water and clothing is first for a short period in one direction and then is reversed so that at the finish of 95 a complete upward and downward stroke 100 of the plunger or drum the clothing in the water occupies substantially the original position occupied upon the beginning of the movement. It is of course evident that the plunger may be operated by hand or by 105 power mechanism of any desired type adapted for the purpose without departing from the spirit of this invention.

Having thus described my invention, what I claim as new and desire to secure by Letters Patent, is:

- 5 1. In a clothes washing machine, the combination of an outer round tub, a movable, hollow bucket plunger through which the clothing and water may pass, and means for operating the same vertically in the outer tub.
- 10 2. In a clothes washing machine, the combination of an outer tub and an inner bucket plunger with an opening in its base through which clothing and water may pass, fitting loosely in said outer tub and vertically movable therein.
- 15 3. In a clothes washing machine, the combination of a tub and a bucket plunger, having a circular wall and a base with a round central opening therein, approximately two-thirds of the diameter of the bucket plunger.
- 20 4. In a washing machine, a vertically movable bucket plunger having a base with a beveled, central, circular opening and a flange adjacent the periphery of said plunger, to agitate and displace water and clothes in combination.
- 25 5. In a washing machine, a tub, a plunger or drum movable vertically therein, said drum having a flange providing a central opening less in diameter than the diameter of the drum, the drum loosely fitting in the tub and being open at the top to receive clothing, and means for moving the drum
- 30 vertically in the tub causing the clothing and water to pass rapidly upwardly and downwardly through the drum.
- 35 6. In a washing machine, a tub, a bucket or drum therein open at each end and having a flange providing a central aperture less in diameter than the diameter of the drum through which the clothing and water may be passed, means for reciprocating the drum in the tub, the displacement of the drum and flange on downward movement of the plunger, causing the water and clothing to be forced upward through the central aperture and then downward therethrough on movement of the drum in the opposite direction.
- 40 7. An agitating device for liquids comprising the combination with a tub or receptacle, of an open ended flanged drum movable vertically therein, the drum having a central opening less in diameter than the diameter of the drum, movement of the drum and consequent displacement causing a rush of fluid through the central aperture.
- 45 8. In a washing machine, a tub for water and clothing and a vertically reciprocable plunger loosely fitting therein and having a central aperture through which the liquid and clothing may pass.

WILLIAM F. BLAKE.
